UNITED STATES PATENT OFFICE.

DAVID H. PIFFARD, OF PIFFARD, NEW YORK.

INCANDESCENT ELECTRIC LAMP.

SPECIFICATION forming part of Letters Patent No. 467,982, dated February 2, 1892.

Application filed May 28, 1891. Serial No. 394,191. (No model.)

To all whom it may concern:

Be it known that I, DAVID H. PIFFARD, a citizen of the United States, and a resident of Piffard, in the county of Livingston and State of New York, have invented a certain new and useful Incandescent Electric Lamp, of which the following is a specification.

My invention relates to a means whereby the parts through which connection is made between the lamp and supply-wire may be protected from damage and liability to short circuits when the lamp is employed in situations where it is exposed to moisture and acid or other fumes tending to attack the parts and form short circuits, as in dye-houses, chemical-works, salt-works, &c. In these situations the ordinary metallic holders for incandescent lamps soon become useless and the penetration of moisture to the internal parts through which connection is made from the supply-wires to the lamp will in time form a short circuit and render the devices useless. Attempts have hitherto been made to avoid this difficulty by employing porcelain lamp-holders, within which the contacts of the lamp-holder are mounted and sealing the supply-conductors into said holder. The devices heretofore employed for this purpose fail to entirely overcome the difficulty, as there is an opportunity for the entrance of moisture around the lamp itself, and, besides, the devices themselves are expensive.

The object of my invention is to render the employment of such holding devices unnecessary and to accomplish the same ends in a cheap, efficient, and durable way. To this end I propose to connect the supply-conductors to the leading-wires in any desired manner, either through suitable contact plates or blocks or by twisting the wires together, and to apply to the lamp-wires and lamp-neck and the supply-conductors a sheath or mass of a solid non-conducting moisture-proof cement, which is of a proper character to remain solid and form a good joint at all temperatures to which the lamp may be exposed during use or under the heating effects of the lamp itself, and will further firmly adhere to the glass of the lamp-globe and to the supply-conductors, so as to form a solid tight moisture-proof seal or joint at such points, and thereby prevent the entrance of moisture or vapors which

would attack the connections, or by lodging in the materials surrounding the lamp-wires form a short circuit between them. The adhering sheath or envelope is preferably put into place by casting it around the parts, which may be readily done by applying a mold or shell of more or less permanent character around the parts and then pouring in the insulating sealing substance in a heated or fluid state, the substance being of proper character to solidify as it becomes cool. The exterior sheath or mold might be simply a piece of paper or card-board which could be removed after the application of the sealing insulating substance, or it might be a piece of hard rubber or other suitable material, which would serve as a permanent protective sheath to prevent the breaking away of the insulating mass. When, however, a mass of insulating substance consisting of the composition invented by me, and hereinafter described, is employed, the exterior protective sheath is not necessary.

I am aware that it has been heretofore proposed to envelop the lamp-wires at the neck of the lamp in a mass of plaster-of-paris; but such substance would be entirely unsuited to the purposes of my invention, as it would not be practically moisture-proof in the situations named. I am also aware that it has been proposed to employ a layer of pitch in combination with a layer of plaster-of-paris superposed upon it and a final layer of pitch; but such substance does not answer the purposes of my invention because it will not remain solid under the temperatures to which a lamp is ordinarily exposed in dye-houses, salt-works, &c., and would in any event become soft or semi-fluid under the heating effects of the lamp itself while in use, so that the insulating moisture-proof substance, such as the pitch, would, if the lamp were inverted in position, become displaced.

The substance employed must be some material which will adhere to the glass of the lamp to form a tight joint and will itself not absorb moisture or fumes, and will also not be readily attacked by acids. It must also be an insulating substance which will not become soft or semi-fluid under the effects of ordinary temperatures, such as it would be exposed to in the ordinary use of the lamp.

In the accompanying drawings, Figure 1 shows in vertical central section a construction embodying my invention. Fig. 2 is a similar view of a modification.

5 B indicates the globe of an incandescent lamp, usually made of glass, and A the incandescent filament.

10 C are the lamp-wires, which pass through the neck of the lamp in the ordinary way, and D are supply-wires, preferably having an insulating cover or jacket and connected to the lamp-wires in any proper manner at E E. The connection here shown is made by twisting the free ends of the lamp-wires around 15 the bared ends of the lamp-conductors.

15 H indicates the insulating enveloping mass of non-conducting substance, which seals the parts effectually against injury and against the formation of short circuits by making a 20 close moisture-proof joint or seal with the material of the globe of the lamp and with the supply-wires D D at the points b a, respectively. This mass of sealing non-conducting and moisture-proof substance may 25 be cast in place around the parts to assume the form shown in Fig. 1 by applying a mold or exterior sheath around said parts and then pouring the substance into the mold and allowing it to harden. The material should 30 be made to come well down over the neck of the lamp as to the points b and be of suitable nature to adhere firmly to the glass and form a good joint. Plaster-of-paris would not suit the purpose, as it will absorb moisture. It is 35 also necessary that the material should be such that in cooling it will not draw away or form an opening at the point of contact with the globe of the lamp. This necessitates the use of some material which will have about 40 the same rate of expansion or contraction of glass when heated.

The substance which I prefer to employ is a compound of rubber, resin, and plaster-of-paris, combined in the proportions of five 45 pounds of rubber to twenty-four of resin and twenty-six of plaster-of-paris, or thereabout, as described in another application for patent filed by me of even date herewith. The rubber and the resin are combined by melting 50 them together and mixing and preferably allowing the heating to go on for a sufficient length of time to drive off the more readily volatilizable materials in the resin. The plaster-of-paris, dry, is then mixed with the other 55 two ingredients thoroughly, and the compound while in a heated softened condition is poured into the mold, as already explained. This substance possesses the additional ad-

vantage of softening only at a comparatively high temperature, and is of a tough horny nature and will adhere firmly to the glass. It is also not acted upon by moisture and very little by such strong acids as sulphuric acid, muriatic acid, &c.

60 It will be seen that the connections from 65 the lamp-wires to the lamp-filament are effectually sealed against entrance of moisture or deleterious vapors and that the seal can be readily and cheaply applied.

70 A mold of paper applied over the parts can be used in casting the sealing substance around the point of connection of the lamp-wires and supply-wires D. It sometimes may be desirable to employ a sheath or mold I, such as indicated in Fig. 2, composed of hard 75 rubber and made sufficiently thick to form a practically permanent base or neck, which may serve likewise as a handle.

80 The insulating substance may be applied at the time of the attachment of the lamp to the supply-wires by the user.

85 What I claim as my invention is—

1. The combination, with an electric lamp and supply-conductors connected to the lamp-wires, of a solid homogeneous sheath or envelope of an adherent non-conducting moisture-proof cement cast around said lamp wires and conductors and adapted to form a tight moisture-proof joint both with the glass of the lamp and the said conductors to adhere 90 to the glass and to the conductors and to remain solid under the temperatures to which it is exposed while the lamp is in use.

2. The combination, with an electric lamp and the insulated supply-conductors having 95 their bared ends connected to the lamp-wires, of an unbroken or homogeneous solid enveloping mass of non-conducting material adhering to and forming a tight moisture-proof joint with the lamp casing or globe and with 100 the insulated conductors above the point of attachment to the lamp-wires, said sealing or cementing substance being of proper character, as described, not to become soft or semi-fluid except at a higher temperature than 105 that to which it is exposed by the heating of the lamp and lamp-conductors or of the atmosphere in the place where it is used.

Signed at Geneseo, in the county of Livingston and State of New York, this 20th day of May, A. D. 1891.

DAVID H. PIFFARD.
